UNITED STATES PATENT OFFICE

FRANK RYGL, OF NEW YORK, N. Y.

HOTEL-ROOM SERVICE TABLE

Application filed March 14, 1928. Serial No. 261,545.

This invention relates to tables, and particularly to tables for serving meals in hotel rooms, the same being in the nature of an improvement upon my co-pending application 5 Serial No. 232,636, filed November 11, 1927. At the present time, where a dinner or a large meal is to be served in a hotel room, it is necessary for the waiter to bring into the room a table upon which the meal is served and to 10 employ an assistant to bring in a service table, thus requiring numerous trips between the room and the pantry until all of the courses have been served. Due to the fact that in the larger hotels the pantry and 15 kitchen are often remote from the room in which the meal is being served, considerable time is consumed in accommodating the guest. It is also obvious that certain foods are necessarily served hot, and hence, makeshift means 20 have been devised for maintaining the foods at the required temperature until served.

In order to overcome the above objectionable features, the present invention comprehends an improved hotel room service table 25 which is constructed in such a manner as to permit of the complete transportation and service of an entire meal by a single waiter at one trip.

More specifically, the invention comprehends an improved hotel room service table 30 which includes a shelf formed on the guest table for supporting a combined serving table and heating cabinet during the transportation of the same between the pantry and the guest 35 room and in which a detachable top for the serving table is carried by and supported from the guest table top so that when the combined heating cabinet and serving table is set up, the detachable top may be associated therewith.

The invention furthermore comprehends an 40 article of furniture for hotel room service including a guest table formed with means for transporting suitable cabinets and receptacles containing foods to be served.

The invention furthermore comprehends a 45 combined heating cabinet and serving table including a detachable top and a foldable 50 supporting means for said detachable top

carried by the combined heating cabinet and serving table.

The invention furthermore embodies a combined heating cabinet and serving table adapted to be transported with and as a part 55 of a guest table, which cabinet is provided with electrical heating means adapted for connection with the house current for heating and maintaining the cabinet and its contents in a heated condition.

Other objects of the invention reside in the provision of a table outfit for serving meals in hotel rooms which embodies the features of 60 simplicity, economy and efficiency.

With the above recited and other objects 65 in view, reference is had to the following description and accompanying drawings, in which there is exhibited one example or embodiment of the invention, while the claims define the actual scope of the same.

In the drawings,

Figure 1 is a perspective view illustrating 70 the guest table with the combined serving table and heating cabinet separated therefrom and set up ready for use.

Figure 2 is a vertical sectional view through 75 the combined heating cabinet and serving table taken approximately on the line 2—2 of Figure 3.

Figure 3 is a similar view taken approximately on the line 3—3 of Figure 2.

Figure 4 is a perspective view of the 80 detachable serving table top removed from the cabinet and folded.

Figure 5 is a view of the guest table with 85 the cabinet and receptacles arranged in place thereon for transportation therewith.

Referring to the drawings by characters 90 of reference, 10 designates generally the main table having a top 11, supporting legs 12 and a shelf 13 which is carried by and preferably disposed near the lower ends of the legs. The legs are preferably provided at the lower ends with rollers or castors 14 to facilitate the rolling of the table over the 95 floor or the supporting surface. The table 10 is designed for the purpose of a bearing table upon which the meal will be served.

A combined serving table and heating cabinet 15 for the reception of hot foods consti- 100

tutes a part of the outfit and is adapted to be arranged on the shelf 13 of the table 10 for transportation with the table to the hotel room where the meal is to be served. The 5 cabinet is provided on its bottom wall with a pair of rollers 16 and a pair of feet 17 so that by slightly elevating the end of the cabinet so that the feet 17 are out of contact with the supporting surface the combined serving 10 table and cabinet 15 may be readily removed from the shelf 13 and moved over the floor or other supporting surface, whereas when the feet are brought into contact with the shelf, floor or the supporting surface the table and 15 cabinet 15 is maintained against shifting movement. The cabinet is provided on its front wall with a doorway or opening by which access may be gained to the interior and the same is closed by doors or other closures 20 which are preferably hinged thereto. Within the cabinet 15 is arranged an electric resistance heating device 19 and, if desired, a shelf or shelves 20. Suitably connected with the heating element is an extension cord 21 25 having a plug 22 which is adapted to be engaged with a baseboard outlet 23 connected with the house current. If desired, a suitable switch 24 may be employed for cutting off or regulating the heat to the heating device 19, 30 the same being preferably mounted on the front wall of the cabinet or table 15. In order to provide a serving surface for the waiter which is of the proper height and spaced above the top wall 25 of the cabinet 35 or table 15, a detachable top 26 is employed which is adapted to rest upon upstanding supporting leaves 27 which are hinged at 28 adjacent the opposite side edges of the upper wall 25 and which leaves during the transportation of the cabinet are adapted to be 40 swung down to a parallel position with the top wall 25, as clearly illustrated in Figure 5. The upper ends of the leaves 27 are adapted to fit between the transverse and 45 longitudinal cleats or strips 29 and 30 which are formed on the under side of the top member 26. In order to hold the leaves 27 in their vertical upstanding supporting position the top member 26 has hinged at 31 to the under 50 side thereof a leaf member 32 which is swingable to a depending position for disposition between the leaves 27, as clearly illustrated in Figures 2 and 3. In order to provide means for transporting the top member 26 with the 55 main table 10 the outer side edges of the transverse cleats or strips 29 are beveled or undercut as at 33 to interfit with the correspondingly beveled or intercut inner edges 34 of the transverse strips or cleats 35 which are 60 provided on the under surface of the top 11 of the main table 10. In order to facilitate the withdrawal of the top 26 from its supported position under the table top 11 a finger engaging slot 36 is provided. The 65 upper wall 25 of the cabinet or table 15 is pro-

vided with a centrally disposed handle 37. In order to provide clearance for the handle when the leaves 27 are swung downwardly the said leaves are provided with medial cut-out portions 38. In addition to transporting the 70 combined serving table and heating cabinet 15 for hot foods, the shelf 13 of the table 10 is designed to also carry a box or cabinet 39 which will be suitably refrigerated for cold foods or iced dishes, and furthermore, a tray 75 40 containing salads, pastries or other articles of food which neither require a heating or cooling agency may be supported upon the cabinet 39 during its transportation with the main table 10 to and from the room. 80

Having thus described my invention, I claim:

1. A combined cabinet and serving table for hotel room service, including a body, a detachable table top member and means carried by the upper wall of the cabinet movable from a normally folded lowered condition to an upright position for supporting the detachable table top member thereabove, said means consisting of leaves hinged to the opposite side edges of the upper wall of the cabinet, transverse and longitudinal cleats formed on the under side of the table top member for receiving the upper edges of the leaves and a leaf carried by the under side of the table top member movable to a position between the leaves of the cabinet. 90

2. As an article of furniture for serving hot meals in hotel rooms, hospital wards or the like, a cabinet adapted to be interiorly heated, a detachable table top member and interengageable means provided respectively on the upper wall of the cabinet and on the under side of the table top member for supporting said table top member in superposed relation to the cabinet, whereby a heat insulated serving service is provided, said interengageable means of connection consisting of leaves hinged to the opposite side edges of the upper wall of the cabinet for swinging movement from a position parallel to the upper wall of the cabinet to a vertical upstanding position, transverse longitudinal cleats formed on the under side of the table top member for abutment with the upper edges of the leaves and a leaf carried by the under side of the table top member movable from a parallel position with respect to said table top member to a depending position between the leaves of the cabinet for retaining said cabinet leaves against the cleats. 110

Signed at New York in the county of New York and State of New York this 12th day of March, A. D. 1928.

FRANK RYGL. 125
